UNITED STATES PATENT OFFICE.

AUGUSTINE CAMPBELL DAVISON, OF BIRMINGHAM, ENGLAND.

DESIGN FOR A LAMP-BODY.

SPECIFICATION forming part of Design No. 29,672, dated November 15, 1898.

Application filed August 13, 1898. Serial No. 688,532. Term of patent 7 years.

To all whom it may concern:

Be it known that I, AUGUSTINE CAMPBELL DAVISON, a subject of the Queen of Great Britain and Ireland, and residing in the city of Birmingham, England, have invented and produced a new and original Design for Lamp-Bodies, of which the following is a specification, reference being had to the accompanying drawings, forming part thereof.

Figure 1 is a side view, Fig. 2 a front view, and Fig. 3 a plan view, of the design.

My design consists in a central cylindrical part 1, surmounted by an enlarged portion or bulb 2, which is larger in diameter than the central portion 1 and which has its edges rounded at 4. At the lower end of the portion 1 is a cylindrical part 3, larger in diameter than the central portion. On the front

side of the central portion 1 is an extension 5 of frusto-conical form, the base-line 6 of which is inclined to the surface of the part 1. A window 7 is formed in each side of the central part 1, and the upper bulb or enlargement is surmounted by a hood 8.

Having described my invention, what I claim as new, and desire to secure by Letters Patent, is—

The design for a lamp-body as herein shown and described.

In witness whereof I have hereunto set my hand in presence of two witnesses.

AUGUSTINE CAMPBELL DAVISON.
